UNITED STATES PATENT OFFICE

SAMUEL HAMMER, OF BROOKLYN, NEW YORK, ASSIGNOR TO UNITED METAL BOX CO.
INC., OF BROOKLYN, NEW YORK, A CORPORATION OF NEW YORK

CABINET DOOR MOUNTING

Application filed February 6, 1930. Serial No. 426,230.

This invention relates to an improved cabinet door mounting, and has for its general object and purpose to provide a very simple and durably constructed means for mounting the door of a medicine cabinet or the like whereby the door may be bodily swung or moved to a position outwardly spaced and laterally offset from the front open side of the cabinet, and then adjusted to a desired angular position with respect to the face of the wall in or upon which the cabinet is secured. Thus, the mirror secured upon the door face may be readily arranged relative to the natural or artificial light source to best suit the convenience of the user.

More specifically, the invention has for one of its objects to provide means hingedly connecting the inner side of the door on its approximate central vertical line with one edge of the front frame of the cabinet, which may be fabricated by the use of simple and inexpensive factory production methods and readily arranged or assembled in connected relation with the door and the cabinet frame to provide a rigid and substantial support which will effectually prevent sagging or vertical displacement of the door relative to the cabinet.

With the above and other objects in view, the invention consists in the improved door mounting for cabinets and in the form, construction and relative arrangement of the several parts as will be hereinafter more fully described, illustrated in the accompanying drawings, and subsequently incorporated in the subjoined claim.

In the drawings, wherein I have disclosed one simple and practical embodiment of my present improvements, and in which similar reference characters designate corresponding parts throughout the several views,

Figure 1 is a top plan view, illustrating a part of the front frame of a cabinet having my present invention applied thereto and showing the door in full and dotted lines in several different adjusted positions relative to said cabinet;

Fig. 2 is a vertical sectional view taken on the line 2—2 of Fig. 1, and

Fig. 3 is an enlarged fragmentary horizontal section taken on the line 3—3 of Fig. 2.

Referring in detail to the drawings, 5 designates a part of the cabinet body which in the illustrated embodiment of the invention 55 is adapted to be set within a mortise or recess cut in the face of a wall and rigidly secured in position by any preferred means. The body wall of the cabinet at the open side thereof has either integrally formed 60 therewith or secured to the cabinet walls, an outwardly extending frame as indicated at 6 having the marginal flange 7 at the outer side thereof disposed in parallel relation with the cabinet walls and the edge of which is 65 adapted to abut against the face of the building wall, said frame covering and concealing the opening or mortise within which the cabinet is mounted.

The door for the open side of the cabinet 5 70 as generally indicated at 8 may be of any approved construction and has suitably secured upon its outer face, the mirror 9. This door when in closed position is adapted to abut closely against the face of the frame 6, 75 and is of such dimensions that the said door projects laterally beyond the top, bottom and side walls of the frame.

The particular improvement constituting the subject matter of this application, resides 80 more particularly in the means whereby the mirror carrying door is mounted or supported for bodily displacement relative to the cabinet frame 6 whereby said door may be disposed in outwardly spaced relation from the 85 open side of the cabinet an appreciable distance and readily adjusted to various angles as best suited to prevailing light conditions. To this end, I provide a plate 10 of appreciable width, the said plate being preferably 90 of comparatively thin gauge steel and of a length somewhat less than the length of the front opening of the cabinet 5. Upon the opposite vertical edges of said plate when the same is cut or stamped from the steel sheet, 95 suitably spaced projections are provided which can be readily turned or bent to form the hinge knuckles indicated at 11 and 12 respectively. At its upper edge and spaced from the hinge knuckle 11, the plate 10 is 100

notched or recessed as indicated at 13 for a purpose which will be presently explained.

To one side of the plate 10, a relatively heavy reinforcing steel plate 14 is secured preferably by spot welds as shown at 15. This plate is of approximately the same length as the plate 10, but is somewhat narrower, one longitudinal edge of the plate 14 being disposed closely adjacent to the hinge knuckles 12 on the plate 10 while the other longitudinal edge of the plate 14 is spaced an appreciable distance from the other edge of the plate 10 on which the hinge knuckles 11 are provided.

15 The frame 6 of the cabinet substantially at the juncture of its front wall with the flange 7, and at suitable vertically spaced points is provided with slots as clearly shown at 16 in Fig. 3 of the drawings and through these 20 slots the hinge plates 17 are disposed, the inner ends of the hinge plates being securely welded upon the inner face of the frame flange 7 as shown at 18. The outer end of each of the plates 17 is formed with a hinge sleeve 25 or knuckle 19.

The door 8 is provided with a back plate 20, and said plate substantially along the vertical center line of the door is provided at vertically spaced points with slots 21 through 30 which hinge plates 22 welded to the inner face of the plate 20 as shown at 23 project, the outer ends of said plates 22 being formed with the hinged sleeves or knuckles 24.

As clearly seen in Fig. 2 of the drawings, 35 the knuckles 11 on one edge of the plate 10 are arranged above and in alignment with the hinge sleeves or knuckles 19 carried by the cabinet frame 6 and are connected therewith by the pintles indicated at 25. The upper knuckle 12 on the other edge of the plate 10 is arranged above the upper hinge knuckle 24 carried by the door plate 20 while the lower hinge knuckle 12 on the plate 10 is disposed below the lower hinge knuckle 24 on 40 the door plate. These aligned hinge knuckles 12 and 24 are connected by the pintles 26. It will be noted that when the parts are thus connected that the reinforcing plate 14 is on the inner side of the plate 10, and faces the 45 open side of the cabinet. The inner vertical edge of plate 14 is spaced a sufficient distance from the hinge knuckles 11 on the plate 10 so that when the door is in its closed position against the cabinet frame 6, said reinforcing 50 plate 14 will be disposed within the front open side of the cabinet body, thus permitting of a very close relation between the back plate 20 of the door and the face of the frame 6. The door 8 is provided adjacent one of 55 its vertical edges with a suitable latching member indicated at 27 to engage a keeper element (not shown) as usually provided on the inner side of one of the body walls of the cabinet.

60 Any desired means may be provided for

limiting the outward hinging or swinging movement of the door carrying plate 10 with respect to the cabinet body, and for this purpose, I have shown the conventional slotted sliding bar 28 horizontally positioned at the upper side of the cabinet and slidably connected with the stop pin or bolt 29 fixed in the top wall of the cabinet body. The outer end of this bar, is pivotally connected as at 30 to the inwardly projecting arm of an angular lug 31, the other arm of which is disposed within the recess 13 in the plane of the plate 10 and rigidly fixed to the reinforcing plate 14 by means of a suitable screw, rivet or other fastening element 32.

Assuming that the door is in a closed position against the face of the cabinet 6, by grasping the edge of the door adjacent to the latch lug 27 and pulling outwardly thereon, the latching means may be readily released. As the door is thereafter bodily moved outwardly and laterally, the supporting plate 10 will freely swing upon the cabinet frame 6 to the position permitted by the slotted link or bar 28 wherein said plate extends substantially at right angles to the plane of the frame 6 of the cabinet, thereby spacing the door from the open side of the cabinet for a distance substantially equivalent to the width of said plate. Having moved the door to such open position, it may then be swung relative to the plane of the plate 10 to various angular positions as indicated at A and B respectively, so that the mirror carried by the door can thus be adjusted as best suited to prevailing light conditions where it will best serve the purpose of the user. There is sufficient friction at the hinge pintles 26 and between the hinge knuckles 12 and 24 to retain the door and mirror in its adjusted position against casual or unintentional pivoting movement with respect to the plate 10.

After the use of the device, the door may be readily swung inwardly and returned to its closed position over the open side of the cabinet where it entirely covers and substantially conceals the cabinet frame 6 and thus adds to the attractive appearance of the room.

From the foregoing description considered in connection with the accompanying drawings, the several structural features of my present invention, as well as its advantages in practical use will be clearly and fully understood. It will be seen that I have provided an adjustable door mounting especially constructed and designed for bath room medicine cabinets which is of simple and durable construction, serviceable and convenient in practical use, and enhances the attractive appearance of cabinets of this type. I have herein disclosed a preferred structural form of my invention whereby manufacture and assemblage of the several parts are greatly facilitated and quantity production expedited so that a device of this kind embodying

such improvements may be manufactured and sold without greater increasing the cost to the consumer over the ordinary medicine cabinet. It is, however, to be understood, that
5 although the described construction is preferable, the several details of the essential features of the present disclosure might also be incorporated in various other structural forms, and I therefore, reserve the privilege
10 of resorting to all such legitimate changes therein as may be fairly embodied within the spirit and scope of the invention as claimed.

I claim:

In combination with a cabinet having an
15 outwardly projecting wall engaging flange at its open side, said flange being provided with vertically spaced openings at one side of the cabinet, plates fixed to the inner face of said flange extending outwardly through
20 said openings and provided with hinge knuckles on their outer ends, a door for the open side of the cabinet having a back plate provided with vertically spaced openings, hinge plates fixed to the inner face of said
25 back plate projecting outwardly through said openings and provided with hinge knuckles on their outer ends, a door supporting plate provided with spaced hinge knuckles on its opposite vertical edges, hinge pintles connect-
30 ing the knuckles on the opposite edges of the plate with the hinge knuckles on the cabinet frame and on the door respectively, and a reinforcing plate secured to the inner face of
35 said door supporting plate and disposed with-
ing the open side of the cabinet when the door is in its closed position and in substantial contact with the wall engaging flange of the cabinet, said door being outwardly and laterally displaceable relative to the cabinet
40 frame and adjustable to various angular positions with respect to the plane of said sup-
porting plate.

In testimony that I claim the foregoing as my invention, I have signed my name hereto.
